(57) **CLAIM**

The ornamental design for a steam appliance, as shown and described.

DESCRIPTION

FIG. 1 is a front view of a steam appliance showing the claimed design;

FIG. 2 is a rear view of the steam appliance of FIG. 1;

FIG. 3 is a top view of the steam appliance of FIG. 1;

FIG. 4 is a bottom view of the steam appliance of FIG. 1;

FIG. 5 is a left view of the steam appliance of FIG. 1;

FIG. 6 is a right view of the steam appliance of FIG. 1;

FIG. 7 is a front, top, right perspective view of the steam appliance of FIG. 1;

FIG. 8 is a front, top, left perspective view of the steam appliance of FIG. 1;

FIG. 9 is a rear, top, right perspective view of the steam appliance of FIG. 1;

FIG. 10 is a rear, top, left perspective view of the steam appliance of FIG. 1;

FIG. 11 is a front, bottom, right perspective view of the steam appliance of FIG. 1;

FIG. 12 is a front, bottom, left perspective view of the steam appliance of FIG. 1;

FIG. 13 is a rear, bottom, right perspective view of the steam appliance of FIG. 1; and

FIG. 14 is a rear, bottom, left perspective view of the steam appliance of FIG. 1;

FIG. 15 is a front view of another embodiment of a steam appliance;

FIG. 16 is a rear view of the steam appliance of FIG. 15;

FIG. 17 is a top view of the steam appliance of FIG. 15;

FIG. 18 is a bottom view of the steam appliance of FIG. 15;

FIG. 19 is a left view of the steam appliance of FIG. 15;

FIG. 20 is a right view of the steam appliance of FIG. 15;

(Continued)

FIG. 21 is a front, top, right perspective view of the steam appliance of FIG. 15;
FIG. 22 is a front, top, left perspective view of the steam appliance of FIG. 15;
FIG. 23 is a rear, top, right perspective view of the steam appliance of FIG. 15;
FIG. 24 is a rear, top, left perspective view of the steam appliance of FIG. 15;
FIG. 25 is a front, bottom, right perspective view of the steam appliance of FIG. 15;
FIG. 26 is a front, bottom, left perspective view of the steam appliance of FIG. 15;
FIG. 27 is a rear, bottom, right perspective view of the steam appliance of FIG. 15; and,
FIG. 28 is a rear, bottom, left perspective view of the steam appliance of FIG. 15.
The broken lines in the drawings depict portions of the steam appliance that form no part of the claimed design.
